UNITED STATES PATENT OFFICE.

FELIX L. McMANUS, OF PHILADELPHIA, PENNSYLVANIA, AND CHARLES P. KIMMEL,
OF GARY, INDIANA.

METAL CROSSTIE.

Continuation of application Serial No. 704,573, filed April 7, 1924. This application filed April 15, 1925.
Serial No. 23,192.*To all whom it may concern:*

Be it known that we, FELIX L. McMANUS and CHARLES P. KIMMEL, citizens of the United States, residing, respectively, at 5 Philadelphia, in the county of Philadelphia, and State of Pennsylvania, and at Gary, in the county of Lake and State of Indiana, have jointly invented certain new and useful Improvements in Metal Crossties, of 10 which the following is a specification.

The present invention relates to metal cross ties.

This application is a continuation as to common subject matter of application bearing Serial No. 704,573, filed April 7, 1924, by the present applicants.

The present invention relates to cross ties such as are used in railroad work for supporting the railroad rails. It has been common practice in the past to provide cross ties of wood, but with the increase of cost due to depletion of the timber supply and due to the need for greater resisting power on account of the increased wheel loads impressed upon the ties by the passing trains, the wooden ties are being replaced by metal ties.

Certain known types of metal ties offer great resistance to load, but lack the resiliency and springiness which the wooden tie possesses, which help to absorb the shocks to which the rail is exposed over its supports, which shocks cause the steel fibres in the rail to crystallize and the rail to lose 30 strength and become broken.

An object of the present invention is to provide a metallic railroad tie which offers a proper resistance to load but which avoids the objections above recited.

40 A further object is to provide a metallic railroad tie of great strength which combines resiliency with relative low cost of production and operation.

45 A further object is to provide a metallic railway tie which combines with the advantages of strength and resilience the advantage of convenience in securing and adjusting a railroad rail upon said tie.

50 A further object is to provide a railroad tie construction involving convenient and

effective means for fastening a railroad rail thereto.

Further objects will appear as the description proceeds.

Referring to the drawings— 55

Figure 1 is a top plan view illustrating one embodiment of the present invention;

Figure 1^a is a view analogous to Figure 1 but showing a modified holding means;

Figure 2 is a sectional view taken along 60 the plane indicated by the arrows 2—2 of Figure 1;

Figure 2^a is a sectional view analogous to Figure 2 but taken along the line 2^a—2^a of Figure 1^a; 65

Figure 2^b is a sectional view analogous to Figures 2 and 2^a but showing another form of rail holding means;

Figure 3 is a sectional view taken along 70 the plane indicated by the arrows 3—3 of Figure 2;

Figure 3^a illustrates a modified form of the cross tie shown in Figure 3;

Figures 3^b and 3^c illustrate further modifications of the structure shown in Figures 75 3 and 3^a;

Figures 4 and 5 are views of a tie rod used for securing the railroad rail to the tie;

Figures 6 and 7 are sectional and side elevational views, respectively, of a tie plate 80 used in connection with the present invention;

Figures 8 and 9 are views of an anchor used in connection with the tie rod illustrated in Figures 4 and 5; 85

Figures 10 and 11 are views of a clamp used for holding the railroad rail in position upon the tie; and

Figures 12 and 13 are views of a gauge piece having cooperative relationship with 90 the clamp shown in Figures 10 and 11.

The numeral 1 indicates a member designed to form supports for railroad rails, one of which is indicated in the drawings by the numeral 2. Said member 1 should 95 be composed of tough resilient metal, rolled steel being a preferred material. The member 1 is rolled from steel to a plate section and given various thicknesses in the rolling processes, which thicknesses constitute char- 100

acteristics of the present invention. As best shown in Figure 3, the member 1 is of substantially tubular cross section, the bottom wall of which is corrugated, as indicated by the numeral 3.

In a general way the member 1 may be described as being a hollow section with four sides and rounded corners. The upper and lower horizontal sides are generally 10 parallel, the upper one being narrower than the lower one. The other two sides are inclined, forming angles preferably, but not necessarily, of equal obliquity with the parallel sides. According to the structure 15 shown in Figure 3, the lower corners 4—4 are of thicker material for reinforcing purposes, said corners 4—4 constituting bulb sections. According to the structure shown in Figure 3^a, the lower corners 4^a—4^a are 20 corrugated longitudinally of the member 1 for reinforcing purposes. The inclined sides or walls, which are indicated by the numerals 5—5, have their upper portions flanged over, as indicated by the numerals 25 6—6 (Figures 3 and 3^a), the adjacent edges of the flanges 6—6 being spaced apart to form a slot 7, the purpose of which will appear hereinafter. Said slot 7 is located 30 along the center line of the upper side of the member 1. It will be understood that though the upper and lower sides of the tie are generally parallel, a certain degree of angularity may occur between the flanged over portions 6—6 without departing from 35 the invention. According to the structure shown in Figure 3^b, the flanges 6^b—6^b are inclined upwardly from the corner portions 5^b—5^b. In operation the flanges 6^b—6^b are 40 adapted to have a swinging motion about the corner portions 5^b—5^b as fulcrums, while the side walls 5—5 have movement about the bulb sections 4—4 as fulcrums. It will be understood, however, that the upward inclination of flanges 6^b—6^b may be 45 dispensed with, if preferred.

It is common practice in railroad work, whether a wooden or metal tie is used, to provide a shoe, commonly called a tie plate, interposed between the tie and the rail 50 which it supports. This tie plate has ordinarily one or more holes on either side of the rail for the reception of spikes (in the case of a wooden tie) or bolts (in the case of steel ties) for holding purposes.

55 A tie plate is illustrated in the drawings of the present application, which tie plate presents certain decided advantages. It is to be understood, however, that wide variations in the type of tie plate may be used 60 without departing from the scope of the present invention.

The illustrated tie plate, indicated by the numeral 8, is preferably made of rolled steel and is given such a cross sectional con-

formation that its under side corresponds 65 to the top of the tie 1. The said tie plate 8 has the rib 9 projecting from the under side thereof, which rib 9 has side walls conforming to the juxtaposed edges of the portions 6—6 of the tie. The side edges 8'—8' 70 of the tie plate 8 are rounded off downwardly to coincide with the rounded corners of the tie 1.

As indicated in Figure 2, the bottom portion of the tie 1 may be corrugated transversely as indicated at 3, said transverse corrugations providing a structure having great strength. Holes 11—11 may be provided in the bottom of the tie whereby 75 draining will be permitted. It will be obvious that the amount of resilience or cushioning can be varied by proper proportioning of the bulbs 4—4 of Figure 3 or the corrugated corner portions 4^a—4^a of Figure 80 3. The amount of resilience is also controlled by the proportioning and the degree of inclination of the sides or walls 5—5 and, in the structure shown in Figure 3^b, the amount of swinging movement of the flanges 6^b—6^b about the corner portions 90 5^b—5^b.

Referring to the means for fastening the railroad rail to the improved tie constituting the subject matter of the present invention, it will be noted that according to the structure shown in Figures 1 and 2 the juxtaposed walls 6—6 of the tie are notched, as indicated by the numerals 12—12, at portions adjacent to one side of the base of the railroad rail 2, said notches providing 95 aligned transversely extending walls 13—13 located on one side of the rail 2. The numeral 14 indicates an anchor bolt, said bolt having a hooked over end portion 15 provided with the slanting gripping face 16. Said anchor bolt is also provided with laterally extending lugs 17—17. The anchor bolt 14 is of a size to pass readily along 100 the slot 17 and may be inserted in position with the lugs 17—17 lying within the tie 1. 105

Surrounding the base of the rail 2 is the electrical insulating member 18, which prevents the grounding of the rail to the metal tie 1. The hooked over end portion 15 of the bolt 14, and particularly the slanting face 16 thereof, firmly grips one side portion of the base of the rail 2, the lugs 17—17 of the anchor bolt abutting against the under side of the portions 6—6 of the tie 1, 110 whereby a clamping effect may be secured. Cooperating with the other side of the base of the rail 2 is the clamp 19, adapted to extend through the slot 7 at the notches 12—12 and having a portion 20 engaging with 115 the under sides of the portions 6—6 of the tie 1. The upper portion of the clamp 19 is provided with the sloping face 21, said face 21 and said portion 20 cooperating to 120 125

- provide a firm grip on the base of the rail 2. Cooperating with the clamp 19 is the gauge piece 22 adapted to abut against the shoulders 13-13.
- 5 The anchor bolt 14 is bent intermediate of its length so that the end thereof opposite to the hooked over portion 15 will, when said anchor bolt is in operative position, slant upwardly to a region above the tie 1.
- 10 Cooperating with the anchor bolt 14 is the anchor 23, which, as indicated in Figure 8, may assume a bifurcated form, the bifurcations thereof being indicated by numerals 24-24. The anchor 23 lies within the 15 notches 23'-23', which are located in the walls 6-6 at a region spaced longitudinally of the tie from the notches 12-12. Said notches 23'-23' provide aligned shoulders 23"-23" extending transversely of the tie.
- 20 Each of the bifurcations 24-24 is provided with a projecting lug 25 adapted to underlie the portions 6-6 of the tie 1, the opposite side of the anchor 23 being provided with projecting lugs 26-26 adapted to abut 25 against the upper side of the walls 6-6 of the tie 1. The space between the bifurcations 24-24 is of sufficient size to receive the anchor bolt 14. The anchor bolt 14 may be screw-threaded at its extremity for the reception of the nut 27, which may be held in place by means of a lock washer 28. In service, the anchor 23 will assume an angular position, as best shown in Figure 2, substantially normal to the slanting portion of 30 the anchor bolt 14, the projecting lugs 25-25 and 26-26 being so disposed as to permit such an angular position.
- Referring now to the functions of the anchor bolt 14 and its cooperating parts, it 40 will be noted that with the anchor bolt in place, with its hooked over end portion 15 in cooperating relationship with one side of the railroad rail 2 and the clamp 19 and gauge piece 22 in cooperative relationship with the other side of the railroad rail 2 and with the anchor 23 in place in the notches 23'-23', the effect of turning down upon the nut 27 will be to hold the railroad rail 2 securely in position, movement to the 45 right as the parts are viewed in Figures 1 and 2 being limited by shoulders 13-13 with which the gauge piece 22 engages. Movement to the left, as the parts are viewed in Figure 2, will be effectively prevented by 50 reason of the engagement between the anchor 23 and the shoulders opposite to the shoulders 23"-23" of the railroad tie. It will be noted that the anchor bolt 14 occupies practically a horizontal position so that vibratory forces communicated by passing trains (which forces are usually in a vertical direction) have little effect upon the anchor bolt 14 and consequently there is little tendency for said anchor bolt to work 55 loose. The fastening members, including
- the anchor bolt 14, clamp 19, gauge piece 22, anchor 23 and nut 27 may be quickly applied and when once in place will permanently remain so. Another advantage of having the anchor bolt 14 in the position 70 illustrated and described is that it is at all times easy to inspect and can be tightened with a minimum of effort if for any reason the nut 27 should become loose. The parts constituting the fastening means may all be 75 manufactured at small cost.
- Figures 1^a and 2^a illustrate modified holding means for the railroad rail. According to the structure shown in these figures, a 80 pair of clamps 29-29 are used, each adapted to have a gripping effect between the base of the rail 2 and the under side of the upper walls 6-6 of the tie, said clamps 29-29 being mounted within notches 30-30 in said upper walls 6-6 adjacent to the longitudinally extending slot 7. The upper jaws of said clamps 29-29 are shown in contact with the electrical insulating member 18. Spaced laterally of the clamps 29-29 are the notches 31-31, which provide aligned transversely disposed shoulders 32-32. Mounted within each of the notches 31-31 is a holding member 33 having the hooked portion 34 adapted to engage the under sides of the walls 6-6 of the tie. 85 Each of said holding members 33-33 has the portion 35, which is adapted to be distorted, as, for example, by means of a blow or blows from a sledge to move into holding relation with a corresponding clamp 29. 90 For this purpose the clamps 29-29 will be provided with recesses 36-36 for the reception of the extremities of the portions 35. The normal cross sectional contour of each of the holding members 33 is illustrated in 95 dotted lines at both the right hand side and the left hand side of Figure 2^a. At the left hand side of Figure 2^a the holding member 33 is shown in dotted lines as it is being inserted in the corresponding notch 31. At 100 the right hand side of Figure 2^a the holding member 33 is illustrated in a position having abutting relationship with the shoulders 32-32 of the notch 31 with the hooked end portion 34 engaging the under side of 105 the walls 6-6. Both sides of Figure 2^a show the holding member 33 after same has been swedged, as, for example, by the use of a sledge, into a position such that the extremities of each of said holding members 110 33-33 has engagement with the corresponding clamp 29 and the corresponding shoulder 32 of notch 31.
- The holding means illustrated in Figures 1^a and 2^a are simple to operate and will be 115 effective in holding the rail in proper position. Said holding means may be readily removed, however, when necessary, with a minimum of inconvenience. The material of holding member 33 will be so chosen that 120 130

while it may be distorted with a sledge, nevertheless it will have sufficient stiffness to remain in its holding position regardless of shocks encountered in service.

5 Figures 2^b and 3^b illustrate a further modified rail holding means. According to the structure shown in these figures, a pair of clamps 29'-29' are used, each adapted to bear upon the base of the rail 2. Said 10 clamps are mounted within notches 30^a-30^a in the upper walls of the tie adjacent to the longitudinally extending slot 7. Said clamps 29'-29' are held in place by means of bolts 30^b-30^b, which bolts 15 have elongated heads 30^c-30^c. Suitable nuts and lock washers may be provided for securely bolting the clamps 29'-29' to the top of the tie. By reason of the engagement of the clamps 29'-29' in the notches 20 30^a-30^a in the top of the tie, said clamps are securely held against longitudinal movement of the tie, and by reason of the action of the bolts 30^b, vertical movement of the clamps is prevented.

25 Figures 2^b, 3^b and 3^c illustrate a modified form of electrical insulating member. According to the form shown in said figures, a piece of tough electrical insulating material is located between the tie plate 8 and 30 the upper part of the tie 1. Said piece of insulating material is indicated by the numeral 37 and has the flaps 38-38 struck down therefrom and located between the rib 9 of the tie plate 8 and the two adjacent 35 walls of the members 6^b-6^b. Said insulating member 37 also has the turned up portions 39-39, which are folded over upon the upper sides of the base of the rail 2. Said upper portions 39-39 are held in place 40 by means of the clamps 29'-29'.

Figure 3^c further shows a construction in which the tie plate 8 fits the upper part of the tie both at the rib 9 and at the side edges 8'-8'. The present invention 45 contemplates such a construction, which, though it does not present the advantages of initial cushioning which are present in the other constructions illustrated, nevertheless presents a very valuable cushioning effect and also presents advantages in common with the other forms of the invention, which advantages will be referred to herein-after.

50 Referring now more generally to the functions of the present invention, it may be repeated that the first requirement of a railroad tie is strength, so that it can properly support the rail and distribute the wheel load to the road bed. Another requirement is resiliency, so as to absorb the shocks applied by the wheel load. The construction embodying the present invention 55 possesses the above mentioned qualities, as will be explained.

60 According to the structure shown in Fig-

ure 3, when the tie is free from load the flange portions 6-6 will be spaced slightly from the rib 9 of the tie plate 8, while the edge portions 8'-8' of said tie plate will be in engagement with the side walls 5-5 of 70 the tie. When the load from the car wheel presses the rail downwardly, this load is transmitted to the tie plate 8. According to the structure shown in Figure 3, the edges 8'-8' of the tie plate 8 will engage 75 the rounded portions of the walls 5-5, forcing them together until their edges are pressed against the rib 9 of the tie plate 8. The tie acts as a cushion, dissipating the effect of the first blow. By reason of 80 the fact that the edges of the portions 6-6 of the tie are now firmly engaged against the rib 9 of the tie plate 8, said parts are substantially locked together and act as an integral member. The initial cushioning action above referred to may be likened to the action of cantilever springs, the side walls 5-5 being fulcrumed about the bulb sections 4-4. After the portions 6-6 are 85 firmly engaged with the rib 9, the action 90 of the tie may be likened to that of an elliptic spring. When the parts are in the positions immediately above referred to, that is--with the portions 6-6 in firm engagement with the rib 9 of the tie plate 8, the tie, due to its elliptic spring action, is 95 adapted to absorb shocks very effectively and at the same time is adapted to sustain without deformation much heavier loads 100 than can be supported by a rigid section of the same weight or which has the same outside dimensions.

According to the structure shown in Figure 3^b, the initial cushioning action is due to a spring action, which may also be likened to a cantilever spring action, the portions 6^b-6^b swinging about the portions 5^b-5^b as fulcrums. According to the structure shown in Figure 3^b, under unloaded conditions the juxtaposed edges of the flanges 110 6^b-6^b closely engage the downwardly struck flaps 38-38 which abut the sides of the rib 9 of the plate 8. The edge portions 8'-8' of the tie plate 8 are, when the tie is not 115 under load, spaced a short distance from the side walls 5-5 and the overlying electrical insulating member 37. When the load from the car wheel presses the rail downwardly, the portions 6^b-6^b are swung downwardly about the portions 5^b-5^b as fulcrums resulting 120 in the movement outwardly of said portions 5^b-5^b, whereby a firm gripping relationship is established between the edge portions 8'-8' of the tie plate 8 and the portions 5^b-5^b of the tie. Flanges 6^b and side 125 walls 5-5 both have cantilever spring actions. The tie acts as a cushion, dissipating the effect of the first blow. Due to the firm gripping effect of the rib 9 and edge portions 8'-8' upon the tie, the tie will there- 130

after act with an elliptic spring action, whereby to provide an effective cushion for heavy loads.

The actions of the tie in the structure shown in Figure 3 and Figure 3^b are quite similar in fundamentals, the initial cushioning being accomplished in each instance by a cantilever spring action, the net result of which is to cause a gripping engagement upon the tie between the rib 9 and the edge portions 8'-8' of the tie plate. After the firm gripping action is accomplished further cushioning action is accomplished by the same movements in each instance.

The improved tie according to the present invention can replace the old wooden ties or the steel ties as now known and used without enlarging the holes in the road bed and without disturbing said road bed. It will, therefore, be understood that the new tie constituting the present invention not only offers as much or greater supporting power or strength as other ties of the same weight, but has, in addition, unusual resiliency and actually functions as a spring cushioning the wheel blows on the rail, thus preserving the rail from the crystallizing effect of repeated blows.

A further advantage of the improved tie constituting the subject matter of the present invention may be explained as follows. A train in passing along the track sways from side to side due to the forces developed by its speed, by unequal loading of the cars and by unbalanced construction particularly in the springs which distribute the weight of the car and its load to the wheels. The result is that in actual practice wheel loads are frequently applied with a greater force to one rail than to the other, causing reactions in the railroad tie, whereby a pair of forces is developed, one downward and the other upward. If the tie is of uniform section (as ties have hitherto commonly been made), said ties being rigid and of equal strength throughout, this pair of forces causes a tendency to lift up the tie beneath the rail where the lesser load is applied, with the result that the tie becomes loosened in the road bed and the track is made uneven, which in turn aggravates the effect of the swaying motion of the train.

The improved tie constituting the subject matter of the present invention is not subject to such action. Even when the tie plate 8 becomes interlocked with the tie, the tie retains its flexibility between the rails, because the slot 7 remains open and permits the top portions 6-6 or 6^b-6^b to act as springs, absorbing any reaction due to unequal loading; so that no pair of forces is developed. Therefore, the region of the tie between the rails does not act as a lever detrimental to the good condition of the track,

which action is unavoidable with other types of ties.

Another advantage accruing from the present invention is that an account of its wedge-shape, with the sides sloping downward and the rounded corners of the bottom edges, it is easy to tamp down the stone or gravel and to securely hold the tie in the road bed. The corrugations on the under side of the tie also assist in holding the tie locked in the road bed and offer resistance to any horizontal forces developed from unequal loads which may tend to push the tie and the track sideways. Furthermore, the corrugated bottom of the tie adds to the strength thereof and prevents any buckling of the same.

A further advantage lies in the fact that the symmetrical shape of the tie insures that the wheel load is always transmitted centrally to the tie and never to one of the side edges thereof. The result of this construction is that no rocking motion occurs when load is applied off center. The present invention, therefore, prevents loosening of the ties in the road bed and the prying loose of the fastenings of the rail.

On account of the secure and dependable means for fastening the rail to the tie and the true support given to the rail by the improved tie and tie plate, the width of rail flange necessary may be materially reduced from present practice, and the material of the rail may be distributed to give a substantial increase in the girder strength of the rail. Expressed in other language, the material which is at present required in the base of the rail may be reduced, and, without increasing the weight of the rail, said rail may be repropportioned to increase the web section for increased girder strength.

Though preferred embodiments of the present invention have been described in detail, it will be clear that many modifications may be made without departing from the scope of the invention. It is intended to cover all such modifications that fall within the scope of the invention as defined by the appended claims.

What is claimed is:

1. A railway cross tie, comprising a hollow member slotted longitudinally, and a plate mounted upon said member, said plate being provided with portions adapted to embrace said hollow member and having a portion located in said slot, said portions being disposed in position to grip said hollow member after a predetermined distortion has occurred.

2. A railway cross tie, comprising a hollow member slotted longitudinally, and a plate mounted upon said member adjacent to said slot, said plate being provided with

- 6 an abutment portion lying in said slot, and other abutment portions cooperating with said first mentioned abutment portion to grip said tie when said tie has been distorted 5 to a predetermined extent.
3. A railway cross tie, comprising a hollow member slotted longitudinally, and a plate mounted upon said member adjacent to said slot, said plate being provided with 10 an abutment portion lying in said slot, and other abutment portions cooperating with said first mentioned abutment portion, said abutment portions being positioned to permit a predetermined distorting movement 15 of said tie and to grip said tie after said predetermined distortion has occurred.
4. A railway cross tie, comprising a hollow member slotted longitudinally, said cross tie having sloping side walls and having 20 its base corners curved and reinforced whereby said side walls may act as springs.
5. A railway cross tie, comprising a hollow member slotted longitudinally, said cross tie having sloping side walls, and means 25 mounted upon said cross tie to cause said tie to operate with a cantilever spring action under initial loads and to cause said tie to act as an elliptic spring after a predetermined flexure has occurred.
6. A railway cross tie, comprising a hollow member slotted longitudinally, said cross tie being symmetrical in cross section and having sloping side walls, top walls, and a base, the edges between said side walls 35 and said base being rounded, and means mounted upon said tie for moving said side walls with a cantilever action, said means being provided with an abutment portion mounted in said slot and with other abutment portions adapted to cooperate with said tie and with said first mentioned abutment portion to cause said tie after a predetermined flexure to operate as an elliptic spring.
7. A railway cross tie, comprising a hollow member slotted longitudinally, a tie plate mounted thereon, said tie plate having abutment portions adapted to engage the outer walls of said cross tie and having an abutment portion adapted to lie within the slot in said member, whereby after a predetermined flexure said portions will grip said tie to cause same to operate as a stiff spring.
8. A railway cross tie comprising a hollow member slotted longitudinally along its top portion and having its bottom portion corrugated with the hills and valleys of said corrugations extending both longitudinally 50 and transversely of the length of said tie.
9. In combination, a railway cross tie, comprising a hollow member slotted longitudinally, a plate mounted upon said member, said plate being provided with portions adapted to embrace said hollow member and 55 having a portion located in said slot, said portions being disposed in a position to grip said hollow member after a predetermined distortion has occurred, a railroad rail carried by said plate, and holding means having portions disposed in said slot for securing said rail to said tie.
10. In combination, a railway cross tie comprising a hollow member slotted longitudinally, a plate mounted upon said member adjacent to said slot, said plate being provided with an abutment portion lying in said slot and other abutment portions cooperating with said first mentioned abutment portion, a rail carried by said tie, and securing means for holding said rail in position on said tie, said securing means having portions disposed in said slot.
11. In combination, a railway cross tie comprising a hollow member slotted longitudinally, a plate mounted upon said member adjacent to said slot, said plate being provided with an abutment portion lying in said slot and other abutment portions cooperating with said first mentioned abutment portion, said abutment portions being positioned to permit a predetermined distorting movement of said tie and to grip said tie after said predetermined distortion has occurred, a rail, and securing means for holding said rail in position on said tie, said securing means including portions located in said slot.
12. In combination, a railway cross tie comprising a hollow member slotted longitudinally, said cross tie having sloping side walls and having its base corners curved and reinforced whereby said side walls may act as springs, a rail, and securing means for holding said rail upon said tie, said securing means including portions extending through said slot.
13. In combination, a railway cross tie comprising a hollow member slotted longitudinally, a tie plate mounted thereon, said tie plate having abutment portions adapted to engage the outer walls of said cross tie and having an abutment portion adapted to lie within the slot in said member, whereby after a predetermined flexure said portions will grip said tie to cause same to operate as a stiff spring, a rail, and means for securing said rail in position on said tie, said securing means including portions extending through said slot.
14. In combination, a railway cross tie having a top wall provided with a longitudinally extending slot, means adapted under the effect of load to urge said tie toward slot-closing position for cushioning purposes, a rail upon said tie, a tie rod lying within said slot and having a hooked over portion engaging one side of the base of said rail, and means including a member engaging said cross tie for holding said tie rod secure.

ly in rail engaging position, said tie rod being disposed relative to said tie and said means to exert a substantially horizontal pull therebetween.

Signed by FELIX L. McMANUS, at Philadelphia, Pennsylvania, this 7th day of April, 1925, and by CHARLES P. KIMMEL, at Gary, Indiana, this 10th day of April, 1925.

FELIX L. McMANUS.
CHARLES P. KIMMEL.
